UNITED STATES PATENT OFFICE.

ALEXANDER CHURCHWARD, OF NEW YORK, N. Y., ASSIGNOR TO GENERAL ELECTRIC COMPANY, A CORPORATION OF NEW YORK.

SYSTEM OF VEHICLE PROPULSION.

1,091,632.

Specification of Letters Patent. Patented Mar. 31, 1914.

Application filed March 10, 1910. Serial No. 548,354.

To all whom it may concern:

Be it known that I, ALEXANDER CHURCHWARD, a citizen of the United States, residing at New York, in the county of New York, State of New York, have invented certain new and useful Improvements in Systems of Vehicle Propulsion, of which the following is a specification.

This invention relates to self-propelled vehicles actuated by one or more electric motors supplied with current from a generator driven by an internal combustion engine. In such installations it is customary to provide the engine with an accelerator, that is, an auxiliary throttle valve in the air intake of the carburetor, said valve being directly operated by the chauffeur to increase or decrease the supply of explosive mixture to the engine and thus vary the speed of the vehicle by varying the current output of the generator. Such a system of speed control is disclosed in the patent to E. J. Berg, No. 801,355, October 10, 1905.

It is found in practice that there is a tendency to use the accelerator too frequently, instead of relying upon it only when heavy grades are to be overcome. The effect of using it when starting or when running light is to cause the engine to race, which is liable to damage it. The present invention aims to prevent this harmful use of the accelerator, and yet secure an efficient operation of the engine at all times.

To this end, my invention consists in a locking device applied to the accelerator, and an electromagnetic releasing device which is responsive to a predetermined generator current.

A further object of the invention is to provide for an automatic opening of the intake when the generator current becomes insufficient to carry the load, as on a heavy grade. This is accomplished by having an auxiliary throttle in the intake, controlled by a solenoid having two differential windings, one in series with the generator and motor, and the other in shunt to the motor armature. As a modification of this idea, the auxiliary throttle may be actuated by two solenoids, one to open and one to close it, the solenoids being controlled by a relay in circuit with the generator.

In the accompanying drawing, Figure 1 is a diagram showing the electromagnetic locking device for the accelerator, com-

bined with the automatically-opening auxiliary throttle, and Fig. 2 shows the accelerator combined with the device for automatically opening and closing an auxiliary throttle by the variations in the generator current.

The generator 1 illustrated is compound wound, and is driven by an internal combustion engine whose intake pipe is shown at 2. The generator supplies current to the motor 3 which propels the vehicle. In the intake pipe are two fuel controlling throttle valves, 4 5, the former being connected by a rod 6 with an operating pedal 7. A locking lever 8 is fulcrumed at 9 near said pedal, and has a notch 10 adapted to engage with said pedal and prevent it from being operated. A spring 11 attached to one end of the lever tends to keep these parts engaged in their locked position. An electromagnet 12 is arranged in proximity to the locking lever, and in a position to withdraw said lever from engagement with the pedal when said electromagnet is sufficiently energized. The winding of this magnet is in series with the generator. The engine and generator run normally at a constant speed, being controlled by a mechanical speed governor, as usual. When the load is light, or the road level, the motor rotates at such speed that its counter-electromotive force cuts down the generator current, so that the electromagnet 12 is not powerful enough to overcome the spring 11, and the pedal remains locked. But when the vehicle strikes a grade or a heavy piece of road, the speed of the motor slackens, and the generator current augments sufficiently to enable the electromagnet to pull down the lever, thereby unlocking the pedal. The chauffeur is then at liberty to press down the pedal and open the throttle valve 4, which will result in speeding up the engine and raising the voltage of the generator current, so as to enable the motor to carry the increased load. In addition to this throttle valve 4, I prefer to provide a second throttle valve 5, whose operating rod 13 is arranged to be actuated by a solenoid having a differential winding, one coil 14 being in series with the generator and the other coil 15 in shunt to the motor armature. A dash-pot 16 dampens the movements of the rod 13. At normal speed, the generator current in the coil 14 is balanced by the

counter-electromotive force of the motor in the coil 15. But when the motor slows down on a grade, the coil 14 becomes relatively stronger and pulls the core 17 to the left, thereby opening the throttle valve 5 and speeding up the generator and consequently also the motor. I prefer to place the windings 12 and 14 in series with each other, so that both throttle valves may be operated, 10 if desired, to secure a prompter response from the engine.

In the modification shown in Fig. 2, the auxiliary throttle valve 5 is actuated by the rod 13, which is connected to a movable core 18 common to two solenoids 19, 20 whose windings are in parallel circuits derived from the generator circuit. The two solenoid circuits are controlled by an interlock 21, whose relay coil 22 is in shunt to the generator. If desired, the relay may have a differential winding 23 in series with the motor. At normal current the relay contacts are open, but a predetermined increase or decrease in said current will cause the 25 closing of the circuit of one or the other of the solenoids 19, 20, thereby effecting an opening or closing of the throttle valve 5 to speed up or slow down the engine. If the generator is wound with a drooping characteristic, the reverse winding 23 is not needed; but if the characteristic is not drooping, and it is necessary to keep the vehicle up to speed on moderate grades, then the reverse winding is used to offset the effect 35 of the main winding of the relay and thus delay the operation of the throttle valve 5. The relay is preferably wound, in any event, to work with a difference in potential of about ten volts, so that no delicate 40 adjustments are necessary.

What I claim as new and desire to secure by Letters Patent of the United States, is—

1. A gasoline-electric system of vehicle propulsion comprising a generator, a motor supplied with current from said generator, an accelerator throttle valve, a pedal for actuating the same, a locking device for said pedal, and an electromagnet for withdrawing said locking device when the generator current exceeds a predetermined value.

2. A gasoline-electric system of vehicle propulsion comprising a generator, a motor supplied with current from said generator,

two fuel controlling throttle valves, a pedal for operating one of said throttle valves, a 55 solenoid for actuating the other of said throttle valves automatically in response to variations in the generator current, and an electromagnetic lock for said pedal responsive to a predetermined value of the generator current, whereby said pedal is unlocked and both of said throttle valves made operable to control the supply of fuel when said generator current exceeds the predetermined value. 65

3. A gasoline-electric system of vehicle propulsion comprising a generator, a motor supplied with current from said generator, two fuel controlling throttle valves, a pedal for operating one of said throttle valves, a 70 core for operating the other of said throttle valves, two windings for said core in parallel branch circuits, a relay responsive to changes in the generator current and controlling the flow of current through said 75 windings, and an electromagnetic lock for said pedal responsive to a predetermined value of the generator current, whereby said pedal is unlocked and both of said throttle valves made operable to control the supply 80 of fuel when said generator current exceeds the predetermined value.

4. A gasoline-electric system of vehicle propulsion comprising a generator, a motor supplied with current from said generator, 85 two fuel controlling throttle valves, a pedal for operating one of said throttle valves and a core for actuating the other, two windings for said core in parallel branch circuits, one for opening said valve and the 90 other for closing it, a relay adapted to close the circuit of either winding, the coil of said relay being in shunt to the generator, and an electromagnetic lock for said pedal responsive to a predetermined value of the generator 95 current, whereby said pedal is unlocked and both of said throttle valves made operable to control the supply of fuel when said generator current exceeds the predetermined value. 100

In witness whereof, I have hereunto set my hand this fifth day of March, 1910.

ALEXANDER CHURCHWARD.
